UNITED STATES PATENT OFFICE

EDWARD A. EVERETT, OF LONG ISLAND CITY, NEW YORK

DESIGN FOR AN INSULATION BLOCK FOR ELECTRIC TERMINALS

Application filed January 22, 1931. Serial No. 38,411. Term of patent 14 years.

To all whom it may concern:

Be it known that I, EDWARD A. EVERETT, a citizen of the United States, residing at Long Island City, in the county of Queens and State of New York, have invented a new, original, and ornamental Design for Insulation Blocks for Electric Terminals, of which the following is a specification, reference being had to the accompanying drawings, forming part thereof.

Fig. 1 is a top plan view, Fig. 2 is a side elevation and Fig. 3 is an end elevation of an insulation block for electric terminals showing my new design.

I claim:

The ornamental design for an insulation block as shown.

EDWARD A. EVERETT.
